UNITED STATES PATENT OFFICE.

JOHN B. SANBORN, OF EVANSTON, ILLINOIS, ASSIGNOR TO ASSOCIATED TRADING CORPORATION, OF MILWAUKEE, WISCONSIN, A CORPORATION OF WISCONSIN.

BUTTON.

Application filed June 4, 1923. Serial No. 643,224.

To all whom it may concern:

Be it known that I, JOHN B. SANBORN, a citizen of the United States, residing at Evanston, in the county of Cook and State 5 of Illinois, have invented new and useful Improvements in Buttons and Other Articles, of which the following is a full, clear, concise, and exact description, reference being had to the accompanying drawing, forming 10 a part of this specification.

This invention relates to buttons and other articles having mechanical attaching means of the rivet or other type.

While not limited thereto the invention is 15 particularly applicable to molded articles and attaching means of the rivet type where such articles require spacing of all or a major portion thereof from the materials to which they are attached.

20 For example buttons in many instances require spacing from the fabrics to which they are attached in order to facilitate buttoning thereof and to prevent distortion and wrinkling of the fabric through which they are passed. As will be understood a button provided with a rivet attaching member is 25 preferably formed with a surface of considerable area to be clamped against the fabric to which the button is attached and hence such surface must be spaced from the body of the button to facilitate buttoning and to avoid wrinkling of the fabric through which the button is passed unless the latter fabric is provided with a special or unduly 30 large buttonhole. On the other hand spacing by forming the button with a molded stem is impractical since it is difficult if not impossible to obtain the desired strength thereof without so proportioning the same 35 as to largely defeat its purpose.

The present invention has among its objects to provide suitable spacing means for buttons or other articles of the aforementioned type.

40 Another object is to provide a metallic spacing element of the above character whereby the same may be made of relatively small diameter.

Another object is to provide a button or 45 other article having a spacing element associated therewith in such manner that the parts are rigidly positioned with respect to each other when the same have been fastened together.

50 Another object is to provide a molded ar-

title having a metallic spacing element attached thereto and projecting therefrom to thereby facilitate the button attaching operation.

Another object is to provide a spacing element for a button or other article which will afford a relatively large area of contact with the fabric or material to which it is attached.

Other objects and advantages of the invention will hereinafter appear.

In the accompanying drawing wherein are illustrated certain of the embodiments which the invention may assume in practice,

Figure 1 is a vertical sectional view showing a button and the attaching means therefor with the spacing device in position, the parts being in unlocked relation to each other;

Fig. 2 is a similar view illustrating a modified form of spacing member with the several parts in permanently interlocked position as the result of the clenching operation;

Fig. 3 is a view similar to Fig. 1 showing another form of spacing member; while

Fig. 4 is a similar view showing still another form of spacing member.

Referring to Fig. 1 the button 5 preferably consists of a suitable material molded to the desired shape with a rivet receiving and clenching cap 6 embedded therein. Passing through the fabric or other material 7 to which it is desired to attach the button is a rivet 8 which is adapted to enter the cap 6 and upon the application of driving pressure to the head 9 thereof the hollow end portion 10 will engage the abutment 11 in the cap to distort or clench said rivet in the manner indicated in Fig. 2.

To properly space the button 5 from the material to which it is thus attached, I provide a substantially cylindrical member 12 having a reduced end portion 13 which is adapted to be inserted in a correspondingly shaped passage extending from the cap 6,

100 said reduced end portion 13 contacting with the cap 6 and being of the same diameter as the opening 14 therein, which opening is only slightly greater than the diameter of

the rivet, to thereby guide and steady the latter while it is being driven. The other end of the member 12 is provided with an outwardly extending annular flange 15 between which and the head 9 of the rivet the material 7 is clamped when the parts are 110

riveted together. It will be noted that the flange 15 provides a large area of contact with the material 7, which is very desirable since it enables the attached article to withstand great pulling strains without tearing away from the material to which it is attached.

In the arrangement illustrated in Fig. 2, the spacing member 12^a is integral with the cap 6^a, the device being otherwise like that shown in Fig. 1. In this arrangement it will thus be apparent that the combined spacing member 12^a and the cap 6^a are embedded in the buttons 5 and the spacing member 12^a thus rigidly held in proper position. The unitary structure of the cap 6^a and spacing member 12^a assists in the proper positioning of said cap during the molding operation, and also provides a button fastening and spacing device consisting of but two separate parts.

Fig. 3 illustrates an arrangement in which the spacing member 12 is separate from the cap 6, but is provided at one end with an outwardly extending annular flange 16 which is embedded in the material forming the button to thereby rigidly hold said spacing member in position. The reduced portion of the spacing member in this case extends outwardly to a point flush with the contour of the button.

In Fig. 4 a passage 17 through the material of the button registers with the opening 14 in the cap 6 and at the outer end of said passage is a countersunk portion 18 adapted to receive the annular flange 19 of the spacing member 12, the structure being otherwise like that shown in the preceding figures.

In attaching a button the rivet is passed through the fabric and into the spacing member and button as illustrated in the several figures, after which the rivet is forced or driven to clench the same within the embedded clenching cap 6 to thereby clamp the fabric between the head 9 of the rivet and the annular flange of the spacing member and thus hold the button in properly spaced relation with respect to the fabric, while employing a spacing member of relatively small diameter having a large area of clamping contact with the fabric.

It will of course be understood that a spacing member of greater or less diameter than that shown may be employed and that the length of the spacing member may be altered as desired.

It will also be apparent that the present invention may be applied to various articles which it is desired to attach to and space from materials or fabrics.

What I claim as new and desire to secure by Letters Patent is:

1. In a device of the character set forth, the combination with a molded composition

article having a recess therein, a headed fastening member to extend through the material to which the article is to be attached and into said recess for clenching engagement therewith, a substantially cylindrical metallic member of relatively small diameter extending from said recess and having an annular flange of relatively large diameter adapted for engagement with said material to thereby space said article from said material.

2. A device of the character set forth comprising a molded composition article having a clenching cap embedded therein and a passage leading to said cap, a metallic spacing member registering with said passage and extending outwardly therefrom, a flange at the outer end of said spacing member, a fastening member adapted to pass through a material and into clenching engagement with said cap and a head on said member adapted to clamp said material against said flange.

3. A button attaching and spacing device comprising in combination, a molded composition button having a clenching cap embedded therein, a passage registering with and extending from the opening in said clenching cap, a metallic spacing member fitted into and extending outwardly from said passage, a flange at the outer end of said spacing member, and a headed fastening member one end of which is adapted to pass through a fabric and said spacing member into clenching engagement with said cap, whereby said fabric will be clamped between the head of said fastening member and said flange.

4. A button attaching and spacing device comprising in combination, a molded composition button having a clenching cap molded therein, a tubular metallic spacing member abutting said cap and extending outwardly from said button, the passage through said spacing member co-operating with the open end of said cap to guide and steady a rivet while being driven into clenching engagement with said cap, and an annular flange at the outer end of said spacing member between which and the head of said rivet a fabric is adapted to be clamped.

5. In combination, a molded composition button having a tubular metallic spacing member embedded therein and extending therefrom, a flange at the outer end of said member, rivet clenching means at the inner end of said member, and a headed rivet the shank of which is adapted for clenching engagement with said last mentioned means.

In witness whereof, I have hereunto subscribed my name.

JOHN B. SANBORN.
